United States Patent Office

Des. 185,672
Patented July 14, 1959

185,672

COMBINED CIGARETTE, MATCH, AND LIGHTER HOLDER

John J. Labe, Temple, Pa.

Application October 24, 1958, Serial No. 53,130

Term of patent 7 years

(Cl. D85—2)

Fig. 1.

Fig. 2.

Fig. 1 is a perspective view of a combined cigarette, match and lighter holder showing my new design; and

Fig. 2 is a perspective view thereof taken from the rear.

The dotted outlines of cigarette and match packages and of a lighter are for illustrative purposes only.

I claim:

The ornamental design for a combined cigarette, match and lighter holder as shown and described.
